[57] CLAIM

The ornamental design for a bracket for automobile air conditioning compressor, as shown and described.

DESCRIPTION

FIG. 1 is a top plan view of the first embodiment of a bracket for an air conditioning compressor showing my new design;

FIG. 2 is a front elevational view thereof;
 FIG. 3 is a left side elevational view thereof;
 FIG. 4 is a right side elevational view thereof;
 FIG. 5 is a top plan view of the second embodiment of a bracket for an air conditioning compressor showing my new design;
 FIG. 6 is a front elevational view thereof;
 FIG. 7 is a left side elevational view thereof;
 FIG. 8 is a right side elevational view thereof;
 FIG. 9 is a top plan view of the third embodiment of a bracket for an air conditioning compressor showing my new design;
 FIG. 10 is a front elevational view thereof;
 FIG. 11 is a left side elevational view thereof;
 FIG. 12 is a right side elevational view thereof;
 FIG. 13 is a top plan view of the fourth embodiment of a bracket for an air conditioning compressor showing my new design;
 FIG. 14 is a front elevational view thereof;
 FIG. 15 is a left side elevational view thereof;
 FIG. 16 is a right side elevational view thereof;
 FIG. 17 is a top plan view of the fifth embodiment of a bracket for an air conditioning compressor showing my new design;
 FIG. 18 is a front elevational view thereof;
 FIG. 19 is a left side elevational view thereof;
 FIG. 20 is a right side elevational view thereof;
 FIG. 21 is a top plan view of the sixth embodiment of a bracket for an air conditioning compressor showing my new design;
 FIG. 22 is a front elevational view thereof;
 FIG. 23 is a left side elevational view thereof;
 FIG. 24 is a right side elevational view thereof.
